UNITED STATES PATENT OFFICE.

FOSCOLO O. HENDRICK, OF EAST ORANGE, NEW JERSEY, ASSIGNOR OF ONE-HALF TO
WILLIAM CHILDS, JR., OF BERNARDSVILLE, NEW JERSEY.

ROLLER-TOWEL CABINET.

1,050,539.

Specification of Letters Patent. Patented Jan. 14, 1913.

Application filed March 27, 1911. Serial No. 617,057.

To all whom it may concern:

Be it known that I, Foscolo O. HENDRICK, a citizen of the United States, and resident of East Orange, in the county of Essex and State of New Jersey, have invented certain new and useful Improvements in Roller-Towel Cabinets, of which the following is a specification.

My invention relates to improvements in 10 towel holders and more particularly to that class of towel holders embodying a supply-roller carrying a roll of toweling from which a clean supply of toweling may be drawn as required, and a take-up roller 15 operative to take up the soiled toweling at substantially the same ratio as that at which the clean toweling is drawn from the supply roller; both of said rollers being mounted in a suitable holder or cabinet and the towel 20 between them hanging from the holder or cabinet in the form of a loop of any desired length.

The object of my invention is to improve 25 towel holders of the type referred to by rendering their operation more efficient and their use more sanitary than heretofore.

To this end the invention consists in the 30 novel construction, arrangement and combinations of parts as hereinafter set forth in detail and pointed out in the claims.

Referring now to the accompanying drawings forming part of this specification; Figure 1 is a perspective view of a roller towel cabinet embodying my invention; 35 Fig. 2 is an enlarged vertical section taken transversely through the center of the same, on the line 2—2 of Fig. 4; Fig. 3 is a similar section taken adjacent one end of the same, on the line 3—3 of Fig. 4; Fig. 4 is 40 an enlarged front elevation with the cabinet and contained parts broken away at one end thereof; and Fig. 5 is a detail view to be hereinafter particularly referred to.

Similar reference characters indicate like 45 parts in the several figures of the drawings.

The several coöoperating parts constituting my device may be mounted upon a frame or support of any suitable design or character; said parts preferably being 50 mounted and contained within an inclosing

cabinet, such as indicated generally by *c*, which is adapted to be located in any convenient position for use.

Suitably secured within this cabinet is a rectangular frame or casting *2*, the opposite vertical sides of which are provided with a series of journal-boxes, indicated at *3*, *4*, *5* and *6*, in which a series of rollers to be presently described are journaled at their opposite ends. The uppermost of these rollers, indicated at *7*, is adapted to carry a roll of toweling, such as *T*, from which the toweling is drawn as required for use, the same being passed around the next lower roller, indicated at *8*, and from thence is led upward through an opening in the front wall of the cabinet and over a guide roller *9* to a convenient position for use at the exterior side of the cabinet as shown. A pair of rollers, indicated at *10* and *11*, operate 70 to engage therebetween the soiled end of the toweling, which is led to them through an opening in the front wall of the cabinet as shown, and take up the same at substantially the same rate as that at which the 75 clean toweling is drawn from the supply roller *7*, whereby a substantially constant length of toweling in loop form is maintained for use at the front or exterior side of the cabinet. Such operation of the take-up rollers *10* and *11* is effected by means of the roller *8*, termed by me an "operating" roller, which is rotated by the frictional engagement therewith of the toweling as the latter is drawn from the supply roller and 80 which imparts such rotative movement to the take-up roller *10* through suitable motion-transmitting means, here shown as gearing *12*. The rotative movement thus imparted to the take-up roller *10* causes it 85 to coöperate with the opposing roller *11* and take up the soiled end of the toweling by drawing it therebetween. When the soiled end of the toweling is thus taken up by the take-up rollers it may be deposited 90 in the cabinet in any desired manner, that is, after being drawn between the rollers it may be deposited loosely in the cabinet or it may be wound directly upon one of the take-up rollers. The latter is the preferable 100

way and the way shown in the present instance. When the toweling is wound upon one of the take-up rollers, one of the latter should be yieldingly supported relatively to the other in order to accommodate the increasing thickness of the toweling as it is wound on the roller. To provide for this the journal-boxes 6 in which the lower roller 11 is journaled are slidably mounted in the frame for vertical movement and are acted upon by springs, as at 13, 13, to yieldingly hold the roller 11 in operative relation to the roller 10.

In order to assure a more positive co-operation between the toweling and the rollers 8 and 10, whereby undue slippage between them will be avoided, said rollers will preferably be provided with a roughened surface, which may be provided by covering them with sand-paper. Also, in some instances, I may employ a pressure roller, such as indicated at 14 in Fig. 5, for holding the toweling against the operating roller 8 to assure a more positive engagement between the same.

A spring brake, in the form of a bar 15 carried by spring arms 16, bears against the roll of toweling on the supply roller and operates to prevent the same from unwinding faster than it is drawn off for use, and also operates to cause the toweling to be drawn from the roll under sufficient tension to assure its proper co-operation with the operating roller 8.

To prevent re-use of the soiled toweling during normal operation of the device, I have provided means for preventing the withdrawal or unwinding of the toweling from the take-up roller. This means may be any suitable for the purpose, the same as here shown being in the form of a clamping device comprising two co-operative clamping members 17 and 18, between which the toweling passes, the member 17 being suitably supported in a stationary position, and the member 18 being pivoted to said stationary member, as at 19, and being operative to swing forward from clamping position relatively to the member 17 under the pulling action of the toweling when the latter is being moved in a direction to be wound upon the take-up roller, and to swing backward to clamping position relatively to the member 17 under the pulling action of the toweling upon any reverse movement of the latter; the said member 18 when in clamping position operating to clamp and lock the toweling against reverse or unwinding movement. When the toweling is thus locked as stated, it is impossible to withdraw, from the take-up roller 11, any portion of the toweling which has been used and then wound up. Except for the particular location of the check device or clamping mechanism consisting of members 17 and 18,

however, a person by pulling backwardly upon the exposed portion of the toweling might stretch the web of toweling upon the take-up roller and thus cause a more or less considerable length of the same, according to the length taken up, to retrograde.

It will be noted that the arrangement of the several rollers is such that the clean and soiled portions of the toweling are separated from each other in order to render the use of the holder sanitary, that is, the clean and soiled rolls are separated and away from contact with each other, and the arrangement of the guide-roller 9 with one side thereof projecting beyond the face side of the cabinet also serves to support the clean run of toweling forward of and away from contact with the rearwardly located soiled run, as shown.

As a means to prevent possibility of the edge of the toweling getting drawn between the intermeshing gears in the event of any undue lateral displacement of the toweling on the rollers, I have located guard-plates 20 in position opposite the intermeshing portions of the gears, as clearly shown in Fig. 3.

What I claim is:

1. A towel holder, comprising a supply roller, a take-up roller, means adapted to be operated by the towel as it is drawn from the supply roller and impart movement to the take-up roller, and means automatically operative to engage the towel and prevent unwinding of the same from said take-up roller.

2. A towel holder, comprising a supply roller, a take-up roller, means adapted to be operated by the towel as it is drawn from the supply roller and impart movement to the take-up roller, and clamping means automatically operative to engage the towel and prevent unwinding of the same from said take-up roller.

3. A towel holder, comprising a supply roller, a take-up roller, means adapted to be operated by the towel as it is drawn from the supply roller and impart movement to the take-up roller, and clamping means engaging the towel between the supply roller and the take-up roller and being operative to automatically release the towel and permit movement of the same when drawn up by the take-up roller and to automatically engage the towel and check movement of the same when drawn in a reverse direction.

4. A towel holder comprising a supply roller, a magazine, a web member partially wound upon said supply roller and partially housed within said magazine, said web member having an exposed portion adapted for use as a towel and located between said supply roller and said magazine, means controlled by tension exerted by hand upon said exposed portion for drawing said exposed portion into said magazine, thus unwinding

another portion from said supply roller, and
a one way check device engaging said web
member directly at a point between said
magazine and said exposed portion to pre-
5 vent retrogression of said member from said
magazine.

Signed at New York, in the county of

New York, and State of New York, this
22nd day of March, A. D. 1911.

FOSCOLO O. HENDRICK.
